Primary Examiner — Caron D Veynar*Assistant Examiner* — Katelin G Kloberg(74) *Attorney, Agent, or Firm* — Luedeka Neely Group, PC**CLAIM**

The ornamental design for a cycling shoe, as shown and described.

DESCRIPTION

FIG. 1 is a perspective view of a cycling shoe of my new design;

FIG. 2 is a front view of the cycling shoe of FIG. 1;

FIG. 3 is a rear view of the cycling shoe of FIG. 1;

FIG. 4 is a left side view of the cycling shoe of FIG. 1;

FIG. 5 is a right side view of the cycling shoe of FIG. 1;

FIG. 6 is a top plan view of the cycling shoe of FIG. 1; and, FIG. 7 is a bottom plan view of the cycling shoe of FIG. 1. The broken lines in the drawings are included for the purpose of illustrating unclaimed features and form no part of the claimed design.
